UNITED STATES PATENT OFFICE.

WILLIAM M. DAVIS, OF WASHINGTON, DISTRICT OF COLUMBIA.

SCARF AND NECKTIE HOLDER.

SPECIFICATION forming part of Letters Patent No. 230,755, dated August 3, 1880.

Application filed June 26, 1880. (Model.)

To all whom it may concern:

Be it known that I, WILLIAM M. DAVIS, a citizen of the United States, residing at Washington, in the county of Washington and District of Columbia, have invented a new and useful Improvement in Scarf, Necktie, and other Fastening or Holding Devices, of which the following is a specification.

My invention relates to an improvement in scarf and necktie holders; and the object of the improvement is to render the loops which fit upon the necktie or scarf and upon the collar capable of clasping these pieces of wearing-apparel with sufficient power to insure the retention of the holder in position, and also the scarf or tie, such clasping hold upon the collar and scarf or tie being produced by having the wire forming the loops drawn inward or inclined at certain points.

This construction of the holder, together with the penetrating-points formed on it, renders it a very efficient device for the purpose mentioned, and for holding a ticket or card on the lapel of the coat, also for retaining the cord of eyeglasses, and for other purposes.

In the accompanying drawings, Figure 1 is a perspective view of the fastening and holding device as manufactured for sale. Fig. 2 is a front view, and Fig. 3 is a vertical section, of a shirt collar, scarf, and my improved fastening or holding device as used together. Fig. 4 is a front view, showing a slightly-modified form.

A represents the improved fastening device; B, a shirt-collar, and C a scarf or tie.

The back clasping-bows, *a a*, of the device A are formed by bending a piece of wire at its middle in a downward direction, in a plane with the length of the wire, and then bending the ends of the wire in an upward direction in a plane at right angles to the first bend; and the front clasping-bows, *b b*, are formed by again bending down the ends of the wire in the same plane that it is bent to form the bows *a a*; and in making these last bends the points *c* of the wire are made to terminate

a considerable distance below the bend of the bows *a*, and these points are sharpened or brought to a fine point either before or after the bends are made in the wire of which the 50 device A is formed.

The bows *a* and *b* are made to act as spring-clasps by drawing the wire inward at opposite points, as indicated at *d*.

In making the first bend in the wire the 55 distance between the turned-down portions thereof should be sufficient to afford a firm hold upon the band of a shirt-collar, and also to locate the two bows *b*, which clasp the tie or scarf, a sufficient distance apart to insure 60 a firm hold upon it, and the points should be of a length sufficient to retain their hold upon the fabric, notwithstanding the scarf or tie may work up and down some distance.

A fastening device similar to the one described may be employed on the back part of the shirt-collar, as well as on the front part, and its pointed ends will be inserted into the back or middle portion of the strap of a scarf, or into the tie, as the case may be. In this 70 application of the device the first bend thereof will come on the inside of the collar-band, the same as in its use upon the front of the collar.

In many instances these fastening and 75 holding devices A will be found useful for holding tickets or cards upon the lapel of a coat, also for fastening the cord of eyeglasses, and when thus used the pointed ends *c* are inserted into the lapel of the coat, and the 80 ticket or card or eyeglass-cord placed into clasping-bows *a a*.

What I claim as my invention is—

An improved scarf and necktie holder, A, consisting of a single piece of wire bent to 85 form end loops or bows, *a a b b*, spring holding-clasps *d d*, and pointed ends *c c*, all substantially as and for the purpose described.

WILLIAM M. DAVIS.
